UNITED STATES PATENT OFFICE

156,715

ASH TRAY OR SIMILAR ARTICLE

Virginia B. Evans, Moundsville, W. Va., assignor to Imperial Glass Corporation, Bellaire, Ohio, a corporation of Ohio

Application June 1, 1949, Serial No. 2,992

Term of patent 14 years

(Cl. D85—2)

To all whom it may concern:

Be it known that I, Virginia B. Evans, a citizen of the United States, residing at Moundsville, State of West Virginia, have invented a new, original, and ornamental Design for an Ash Tray or Similar Article, of which the following is a specification, reference being had to the accompanying drawing, forming a part thereof.

Figure 1 is a top plan view of an ash tray or similar article, showing my new design; and

I claim:

The ornamental design for an ash tray or similar article, substantially as shown.

VIRGINIA B. EVANS.
